PUMP

Filed June 23, 1923

2 Sheets-Sheet 2

Inventor:

Arthur C. Hopkins,
Bridgemanforth, Lee, Chittenden & Niles,
St. Louis.

UNITED STATES PATENT OFFICE.

ARTHUR C. HOPKINS, OF NILES, MICHIGAN.

PUMP.

Application filed June 23, 1923. Serial No. 647,295.

To all whom it may concern:

Be it known that I, ARTHUR C. HOPKINS, a citizen of the United States, residing at Niles, in the county of Berrien and State 5 of Michigan, have invented a new and useful Improvement in Pumps, of which the following is a specification.

This invention relates to pumps and the like, and is fully described in the following specification, as shown in the accompanying drawings, in which Figure 1 is a vertical, longitudinal section through a pump embodying my invention. Figure 2 is a transverse section in line 2—2 Figure 15 1, and Figure 3 is a similar section in line 3—3 Figure 1.

This pump comprises a main casting 10 open at the top and having a cover 11 secured thereto by means of bolts 12. A crank shaft 13 is journaled in suitable bearings 14 carried by the main casting 10 and has a gear 15 keyed thereon, which meshes with a pinion 16 which is keyed to a shaft 17 which is driven by any suitable source of power not shown.

The crank-shaft, as illustrated, has four cranks which are set 90° apart. Each crank has a connecting rod 18 connected thereto at its upper end and the lower end of the 30 connecting rod being hingedly mounted on a piston pin 19 which is carried by a piston 20 which is slidably mounted in the cylinder 21.

The lower end of the cylinder 21 communicates with the sump 22 through an inlet passage 23 in which is formed a valve seat 24. The valve 25 is adapted to rest upon the valve seat 24 and has a stem 26 which is slidably in the valve stem guide 27. 40 A spring 28 normally holds the valve 25 upon its seat.

The lower end of the cylinder 21 also communicates with the discharge line 29 through an outlet opening 30 which has an outwardly facing valve seat 31. This is normally closed by a valve 32, the valve being held upon its seat by the spring 33.

This pump is intended to pump oil, or other liquids, and it will be understood from 50 the foregoing, that as the crank-shaft 13 is turned so as to lift the piston 20, the suction produced in the cylinder 21 will cause the oil in the sump 22 to lift the valve 25, permitting some of this oil from the sump 55 to flow into the lower part of the cylinder 21. As the piston descends, this oil will be

forced out past the valve 32 into the discharge line 29, in a well-known manner.

Referring now to Figure 1, it will be observed that the end of the main casting 10 has a reduced portion 10* which has a conical opening 34 in which is rotatably mounted a plug valve 35 having a squared end 36 adapted to receive a wrench whereby it may be turned. A curved passage 37 is formed in this plug valve having sides 38 which are separated from the passage 39.

As the plug valve 35 is shown in Figure 1, the passage 37 communicates with the end 29* of the discharge line and with the pipe 40. At the same time, the pipe 41 communicates through the passage 39 with the opening 42 which opens into the upper open space in the main casting 10.

It will thus be seen that with the plug 75 valve 35 set, as shown in Figures 1 and 3, the liquid forced out through the discharge line 29 will pass through the passage 37 into the pipe 40. From the pipe 40 the liquid is returned, still under pressure, through the pipe 41 and is forced up 80 through the passage 39 and opening 42 into the upper portion of the pump which is preferably kept nearly full of oil.

To reverse the direction of flow of the 85 liquid through the pipe 40 and 41, the plug valve 35 is rotated in a clockwise direction through about 45° so that the passage 37 is brought directly into communication with the passage 41. The liquid delivered by the 90 pump is then forced directly into the pipe 41 from the end of the discharge line 29*. This liquid then returns through the pipe 40 and passes around the outside of the passage 37 through the passage 39 and up 95 through the opening 42 into the upper portion of the pump.

Under some circumstances, it is necessary 100 that the rate of discharge from the pump shall vary with a given crank-shaft speed, and for this purpose, I have provided a series of openings 43, 44, 45 and 46, arranged one above the other in the side of the cylinder 21 so that they are successively uncovered by the piston as it travels outwardly. A plate 47 lies along the back of all of these holes and is held between lateral guides 48 and 49.

In the position shown in Figures 1 and 110 2, these lateral openings are closed by the plate 47 which is adjustably held upon its seat by means of screws 50. The plate is

provided, however, with sets of variable openings 51, 52, 53 and 54 which correspond in height with the openings 43, 44, 45 and 46. The plate 47 may be moved to the left from the position shown in Figure 1 by means of the rod 55 which is attached thereto. As the plate is moved to the left, the upper openings 54 communicate with the upper holes 46. With the plate in this position and the crank-shaft in operation, the vacuum of the cylinder 21 will be broken as soon as the piston 20 uncovers the upper hole 46 and the liquid will then be drawn through this hole and the opening 54 into the cylinder 21. As the piston descends, the liquid will be forced back through this hole into the sump 22 until the piston passes the hole 46. With this hole closed by the piston the pressure generated in the cylinder 21 will force the liquid out into the discharge line 29, as before, for the rest of the stroke.

By moving the plate 47 still farther to the left, the holes 45, 44 and 43 are successively uncovered, thereby decreasing the amount of liquid forced into the discharge line on each downward stroke of the piston. With the holes 43 completely uncovered, no liquid will be forced into the discharge line.

This pump is particularly adapted to be used in connection with a differential turbine which I have designed for use in driving motor vehicles and in this connection the range of speeds and flexibility obtainable by this combination has been found to produce very desirable results.

While I have shown and described certain embodiments of my invention, it is to be understood that it is capable of many modifications. Changes, therefore, in the construction and arrangement may be made without departing from the spirit and scope

of the invention as disclosed in the appended claims, in which it is my intention to claim all novelty inherent in my invention as broadly as possible in view of the prior art. 45

What I claim as new, and desire to secure by Letters Patent, is:

1. A pump having a cylinder, a piston reciprocable therein, inlet and outlet valves for said cylinder, a series of openings in the walls of said cylinder which are successively uncovered by said piston as it reciprocates and means for adjustably closing said openings.

2. A pump having a cylinder, a piston reciprocable therein, inlet and outlet valves for said cylinder, a series of openings in the walls of said cylinder which are successively uncovered by said piston as it reciprocates, and a sliding plate having holes therein for adjustably closing said openings.

3. A pump having a cylinder, a piston reciprocable therein, a sump, inlet and outlet valves for said cylinder, the inlet valves communicating with said sump, a passage 65 communicating with said cylinder and sump which is uncovered by said piston as it reciprocates, and means for progressively closing said passage longitudinally of the cylinder to control the volume delivered by 70 said pump.

4. A pump having a cylinder, a piston reciprocable therein, a sump, inlet and outlet valves for said cylinder, the inlet valves communicating with said sump, a passage 75 communicating with said cylinder and sump which is uncovered by said piston as it reciprocates, and a sliding plate for progressively closing said passage longitudinally of the cylinder to control the volume delivered by 80 said pump.

ARTHUR C. HOPKINS.
